UNITED STATES PATENT OFFICE.

PROSPERO TOMMASONI, OF NEW BRITAIN, CONNECTICUT.

DESIGN FOR A HANDLE.

Application filed August 3, 1922. Serial No. 3,280. Term of patent 7 years.

To all whom it may concern:

Be it known that I, PROSPERO TOMMASONI, a citizen of the United States, and a resident of New Britain, county of Hartford, and State of Connecticut, have invented a new, original, and ornamental Design for a Handle, of which the following is a specification, reference being had to the accompanying drawing, forming a part thereof.

In said drawing:

Fig. 1 is a front view of an ornamental handle embodying the design of my invention.

Fig. 2 is a side view of the above figure.

I claim:

The ornamental design for a handle substantially as shown.

PROSPERO TOMMASONI.
